CLAIM

The ornamental design for a wrist light, as shown and described.

DESCRIPTION

FIG. 1 is a perspective view of a wrist light showing my new design therefore;

FIG. 2 is a view similar to FIG. 1 of my design with the lights in a folded position;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof;

FIG. 8 is a rear elevational view thereof;

FIG. 9 is a top plan view thereof in an open position for storage and shipping of my wrist light design; and,

FIG. 10 is a bottom plan view thereof in the open position.
